[57] CLAIM

The ornamental design for a stretching exerciser for golfers or the like, as shown and described.

DESCRIPTION

FIG. 1 is a perspective view of a stretching exerciser for golfers or the like, showing my new design, shown broken away for convenience of illustration;

FIG. 2 is a reduced top plan view thereof;

FIG. 3 is an enlarged left end elevational view thereof;

FIG. 4 is an enlarged right end elevational view thereof;

FIG. 5 is an enlarged cross-sectional view thereof, taken along line 5—5 of FIG. 2;

FIG. 6 is a fragmentary perspective view of the right end, showing the end portion partially extended; and,

FIG. 7 is a fragmentary perspective view of the right end, showing the end portion fully extended.
